CLAIM

The ornamental design for a battery pack adaptor, as shown and described.

DESCRIPTION

FIG. 1 is a top-rear-right side perspective view of a battery pack adaptor of the present invention.

FIG. 2 is a front elevation view of the battery pack adaptor of FIG. 1.

FIG. 3 is a left side elevation view of the battery pack adaptor of FIG. 1.

FIG. 4 is a rear elevation view of the battery pack adaptor of FIG. 1.

FIG. 5 is a right side elevation view of the battery pack adaptor of FIG. 1.

FIG. 6 is a top plan view of the battery pack adaptor of FIG. 1.

FIG. 7 is a bottom plan view of the battery pack adaptor of FIG. 1.

FIG. 8 is a bottom-front-right side perspective view of the battery pack adaptor of FIG. 1.

FIG. 9 is a bottom-rear-right side perspective view of the battery pack adaptor of FIG. 1.

FIG. 10 is a bottom-rear-left side perspective view of the battery pack adaptor of FIG. 1; and,

FIG. 11 is a bottom-front-left side perspective view of the battery pack adaptor of FIG. 1.

The broken lines present in the figures are included for the purpose of illustrating portions of the article that form no part of the claimed design.
